IGNITION SYSTEM FOR INTERNAL-
COMBUSTION ENGINES

Marion Mallory, Detroit, Mich.

Application October 19, 1944, Serial No. 559,423

8 Claims. (Cl. 123—117)

This invention relates to an ignition system for an internal combustion engine and more particularly to an ignition timer which is automatically controlled in accordance with the speed and load.

For smooth idling, an extreme retardation of the timing is necessary, but upon a slight opening of the throttle, there should be an appreciable immediate advance of the timing. Following this, there should be a further gradual advance as the speed increases, but when the engine is working under full load with wide open throttle at either low or high speeds, it is desirable to retard the advance to some extent to prevent detonation.

This invention contemplates an ignition system for an internal combustion engine which will automatically time the spark as outlined above.

In pressure ignition systems the intake passageway pressures are used to actuate a suction device for controlling the timer. The suction device is connected with an orifice in the intake passageway on the atmosphere side of the throttle valve when the throttle is in idle position. As the throttle opens the orifice passes on to the engine side of the throttle valve. In all of these ignition systems wherein the manifold vacuum is used to advance the timer the problem has been that of getting a sufficient and early enough spark advance as the throttle opens from idle position. To make the spark advance early enough, in some instances the orifice has been positioned immediately adjacent to the throttle valve when in idle position so that the spark will immediately start to advance on the slightest opening movement of the throttle but when this is done the velocity is so high between the throttle valve and the orifice that the spark advances too much. As a matter of fact, the velocity of the motive fluid by the orifice when the throttle valve is only slightly open creates a vacuum at the orifice which is even higher than the manifold vacuum. To avoid too high spark advance when the throttle is only slightly opened, others have located this orifice somewhat above the throttle valve when closed to avoid the venturi or velocity effect but in such cases the spark advance comes in too late, in other words the throttle must be open for a considerable distance before the spark will be advanced and, as it is necessary to advance the spark immediately when the throttle is moved away from idle position to get the best results, it is necessary to have the orifice set very close to the throttle.

Of course, as stated, in the usual pressure ignition system, if the orifice is set close to the throt-

tle, there is too much spark advance when the throttle is slightly moved towards an open position due to the high velocity passing by the throttle tip. Furthermore, once this high suction is

5 in the suction device the spark will not retard quickly enough to prevent spark knock when the throttle is opened suddenly even though the vacuum in the manifold does decrease slightly due to opening the throttle.

10 It is an object of my invention to produce an ignition system wherein the intake passageway vacuum is used to advance the spark at low engine speeds and as the throttle valve is moved only slightly open from idle position, and to avoid 15 the vacuum created by the velocity between the throttle valve and the orifice from excessively advancing spark.

A further object is to cause the vacuum in the suction device to decrease more rapidly when the 20 throttle is suddenly opened.

The first object is accomplished by utilizing the 25 vacuum produced by the velocity between the throttle valve and the orifice to control a valve which controls communication between the suction device and the intake passageway on the engine side of the throttle valve.

The second object is accomplished by shutting off the communication between the suction 30 device that advances and retards the spark and the intake manifold when the manifold vacuum drops to a predetermined point due to opening the throttle valve.

The drawing shows my ignition system.

35 The parts of my invention are as follows: intake passageway 1, inlet opening 2, outlet to the engine 3, throttle valve 4, valve shaft 5, crank 6 fixed on the outer end of valve shaft 5, venturi 7 in the intake passageway 1, suction device 8, flexible diaphragm 9, suction chamber 10, compression spring 11, timer cam 12, plate 13, circuit breaker 14 mounted on plate 13, rod 15 fixed at one end to diaphragm 9 and pivoted at the other end to plate 13, conduit 16 connecting suction 40 chamber 10 with branch conduit 17 leading to orifice 18 in venturi 7 and with branch conduit 19 leading to orifice 20 in intake passageway 1 on the engine side of valve 4, piston valve 21 in cylinder 22 for controlling communication between conduit 16 and orifice 20, compression spring 23 tending to keep valve 21 closed, orifice 24 positioned immediately adjacent to, and on the atmosphere side of, throttle valve 4 when in idle position, air bleed 25 for cylinder 22, and orifices 55 26 and 27.

The operation of my device is as follows: assuming throttle valve 4 is closed with orifice 24 on the atmosphere side of valve 4, spring 23 holds piston valve 21 over orifices 26 and 27 to thereby cut off orifice 20 from conduit 16. At this time the pressure in suction chamber 10 will be atmospheric and the distributor or timer will be in idle position, that is, retarded. If throttle 4 is moved toward open position, the high velocity of the motive fluid flowing by orifice 24 will create a vacuum in cylinder 22 thereby moving piston valve 21 toward the left, compressing spring 23 and placing orifices 26 and 27 in communication through circumferential groove 28 in spool valve 21 so that the intake manifold vacuum will act through orifice 20, conduits 19 and 18, suction chamber 10, flexible diaphragm 9, and rod 15 to rotate plate 13 clockwise to advance the spark. However, this advance in the spark timing will not be as high as it would if orifice 24 were connected directly to conduit 16 and valve 21 eliminated.

If throttle 4 is moved wide open, then the vacuum at orifice 24 is substantially eliminated so that valve 21 moves toward the right, closing off orifice 20 from conduit 16 so that the suction device 8 is now influenced by the vacuum created by the velocity of the fluid flowing through venturi 7 past orifice 18. Thus, for wide open throttle or full load operation the ignition timing advance is controlled by the vacuum created by the motive fluid flowing through venturi 7 past orifice 18 and for part throttle or load operation the ignition timing is controlled by the intake passageway suction at orifice 20 as bled down through orifice 18 and passageway 17.

In the event throttle valve 4 is moved slightly past orifice 24 the full manifold vacuum force will be on the diaphragm 9 which will give considerable spark advance and, if the throttle is opened further to cause a further drop in the manifold vacuum, spring 23 will move piston to the right causing the manifold vacuum to be shut off from the suction device and the spark will be retarded to prevent spark knocks on acceleration when the throttle is moved only a short distance, so it can be seen that the spring 23 is the main control or varying factor of the vacuum forces in the suction device instead of the throttle 4.

I claim:

1. In an internal combustion engine having an intake passageway and a throttle valve controlling the flow of motive fluid through the passageway, the combination of an ignition timer, a suction device for controlling said ignition timer, an orifice positioned in the intake passageway on the atmosphere side of the throttle valve in all positions of the throttle valve, a second orifice positioned in the intake passageway on the engine side of the throttle valve in all positions of the throttle valve, conduits connecting the said orifices with the suction device, a third orifice in the intake passageway positioned adjacent to and on the atmosphere side of the throttle valve when in idle position, and suction responsive valve means controlling communication between the suction device and the second orifice, said valve means shutting off communication between the second orifice and the suction device when the throttle valve is in idle position and responding to the suction created by the fluid flow by the third orifice as the throttle valve opens from idle position to place the second orifice in communication with the suction chamber of said

suction device whereby the ignition timer is actuated to advance the spark.

2. In an internal combustion engine having an intake passageway and a throttle valve controlling the flow of motive fluid through the passageway, the combination of an ignition timer, a suction device for controlling said ignition timer, an orifice positioned in the intake passageway on the atmosphere side of the throttle valve in all positions of the throttle valve, a second orifice positioned in the intake passageway on the engine side of the throttle valve in all positions of the throttle valve, conduits connecting the first and second orifices with the suction device and with each other, a third orifice in the intake passageway positioned immediately adjacent to and on the atmosphere side of the throttle valve when closed for idle, a cylinder communicating with said third orifice, a valve in said cylinder controlling communication between the second orifice and the suction device and between the second orifice and the first orifice, said valve being closed when the throttle valve is in idle position and responding to the suction created by the fluid flow by the third orifice as the throttle valve opens from idle position to place the second orifice in communication with the first orifice and the suction device whereby the suction device responds to the suction in the intake passageway and actuates the ignition timer to advance the spark.

3. In an internal combustion engine having an intake passageway and a throttle valve controlling the flow of motive fluid through the passageway, the combination of an ignition timer, a suction device for controlling said ignition timer, a venturi in the intake passageway positioned on the atmosphere side of the throttle, an orifice positioned in the venturi, a second orifice positioned in the intake passageway on the engine side of the throttle valve in all positions of the throttle valve, conduits connecting the said orifices with the suction device, a third orifice in the intake passageway positioned adjacent to and on the atmosphere side of the throttle valve when in idle position, and suction responsive valve means controlling communication between the suction device and the second orifice, said valve means shutting off communication between the second orifice and the suction device when the throttle valve is in idle position and responding to the suction created by the fluid flow by the third orifice as the throttle valve opens from idle position to place the second orifice in communication with the suction chamber of said suction device whereby the ignition timer is actuated to advance the spark.

4. In an internal combustion engine having an intake passageway and a throttle valve controlling the flow of motive fluid through the passageway, the combination of an ignition timer, a suction device for controlling said ignition timer, a venturi in the intake passageway positioned on the atmosphere side of the throttle, an orifice positioned in the venturi, a second orifice positioned in the intake passageway on the engine side of the throttle valve in all positions of the throttle valve, conduits connecting the first and second orifices with the suction device and with each other, a third orifice in the intake passageway positioned immediately adjacent to and on the atmosphere side of the throttle valve when closed for idle, a cylinder communicating with said third orifice, a valve in said cylinder controlling communication between the second orifice and the suction device whereby the ignition timer is actuated to advance the spark.

fice and the suction device and between the second orifice and the first orifice, said valve being closed when the throttle valve is in idle position and responding to the suction created by the fluid flow by the third orifice as the throttle valve opens from idle position to place the second orifice in communication with the first orifice and the suction device whereby the suction device responds to the suction in the intake passageway and actuates the ignition timer to advance the spark.

5. In an internal combustion engine having an intake passageway and a throttle valve controlling the flow of motive fluid through the passageway, the combination of an ignition timer, a suction device for controlling said ignition timer, an orifice positioned in the intake passageway on the atmosphere side of the throttle valve in all positions of the throttle valve, a second orifice positioned in the intake passageway on the engine side of the throttle valve in all positions of the throttle valve, conduits connecting the said orifices with the suction device, a third orifice in the intake passageway positioned adjacent to and on the atmosphere side of the throttle valve when closed for idle, a cylinder communicating with said third orifice and connected into the conduit between the second orifice and the suction device, a piston valve in said cylinder closing off the conduit between the second orifice and the suction device when the throttle valve is in idle position, said piston valve responding to the suction created by the fluid flow by the third orifice as the throttle valve immediately opens from idle position to place the second orifice in communication with the suction device whereby the ignition timer is actuated to advance the spark.

6. In an internal combustion engine having an intake passageway and a throttle valve controlling the flow of motive fluid through the passageway, the combination of an ignition timer, a suction device for controlling said ignition timer, a venturi in the intake passageway positioned on the atmosphere side of the throttle, an orifice positioned in the venturi, a second orifice positioned in the intake passageway on the engine side of the throttle valve in all positions of the throttle valve, conduits connecting the said orifices with the suction device, a third orifice in the intake passageway positioned adjacent to and on the atmosphere side of the throttle valve when closed for idle, a cylinder communicating with said third orifice and connected into the conduit between the second orifice and the suction device, a piston valve in said cylinder closing off the conduit between the second orifice and the suction device when the throttle valve is in idle position, said piston valve responding to the suction created by the fluid flow by the third orifice as the throttle valve immediately opens from idle position to place the second orifice in communication with the suction device

whereby the ignition timer is actuated to advance the spark.

7. In an internal combustion engine having an intake passageway and a throttle valve controlling the flow of motive fluid through the passageway, the combination of an ignition timer, a suction device for controlling said ignition timer, an orifice positioned in the intake passageway on the engine side of the throttle valve in all positions of the throttle valve, a conduit connecting the orifice with the suction device, a second orifice in the intake passageway positioned adjacent to and on the atmosphere side of the throttle valve when closed for idle, said second orifice passing on to the engine side of the throttle valve during the initial opening movement of the throttle valve, and suction responsive valve means controlling communication between the suction device and the first orifice, said valve means shutting off communication between the first orifice and the suction device when the throttle valve is in idle position and responding to the suction created by the fluid flow by the second orifice immediately as the throttle valve opens from idle position to thereby place the first orifice in communication with the suction chamber of the suction device whereby the ignition timer is actuated to advance the spark.
8. In an internal combustion engine having an intake passageway and a throttle valve controlling the flow of motive fluid through the passageway, the combination of an ignition timer, a suction device for controlling said ignition timer, a venturi in the intake passageway positioned on the atmosphere side of the throttle, an orifice positioned in the venturi, a second orifice positioned in the intake passageway on the engine side of the throttle valve in all positions of the throttle valve, conduits connecting the said orifices with the suction device, a third orifice in the intake passageway positioned adjacent to and on the atmosphere side of the throttle valve when closed for idle, a cylinder communicating with said third orifice and connected into the conduit between the second orifice and the suction device, a piston valve in said cylinder closing off the conduit between the second orifice and the suction device when the throttle valve is in idle position, said piston valve responding to the suction created by the fluid flow by the third orifice as the throttle valve immediately opens from idle position to place the second orifice in communication with the suction device whereby the ignition timer is actuated to advance the spark, and resilient means for closing said piston valve when the throttle valve is substantially wide open whereby the suction device responds to the vacuum created at the first orifice by the velocity of the motive fluid flowing through the venturi to control the spark advance.

MARION MALLORY.
